JOSEPH T. NORMAN, OF NANTICOKE, PENNSYLVANIA.

SPARK-PLUG.

1,243,205.

Specification of Letters Patent. Patented Oct. 16, 1917.

Application filed February 2, 1915. Serial No. 5,717.

To all whom it may concern:

Be it known that I, JOSEPH T. NORMAN, residing at Nanticoke, in the county of Luzerne and State of Pennsylvania, have invented certain new and useful Improvements in Spark-Plugs, of which the following is a specification.

My invention relates to certain new and useful improvements in spark plugs and the invention primarily has for its object to provide what I term a solid and permanently constructed plug in which the inner electrode is embedded in a solid insulating substance to relatively permanently retain the electrode in place.

A further object of the invention is to provide means whereby the plug points are kept from fouling, by oil and carbon deposits, as much as possible.

In its generic nature, the invention comprises an outer threaded section adapted to be screwed in the spark plug opening of an internal combustion engine, and form one of the electrical connections, the threaded socket section carrying the sparking point and serving as a holder or retainer for the inner electrode or sparking point, the inner electrode being of rod-like form and embedded in a mass which fills the outer section and is itself composed of a cementitious composition so as to readily secure the inner electrode in place and effect a tight joint the projecting points of the plug being protected by a screen which serves to restrain the oil from splashing by virtue of carbon deposits.

The improved plug also includes an upwardly extending section of heat insulating material, the same being preferably secured in place by a cap nut threaded onto the inner electrode.

In its more subordinate nature, the invention also includes those novel details of construction, combination and arrangement of parts all of which will be first fully described, then be specifically pointed out in the appended claims, and illustrated in the accompanying drawing, in which:

Figure 1 is a longitudinal section of the preferred form of the invention.

Fig. 2 is a detail perspective view of a portion of the same, the screen being omitted.

Fig. 3 is a cross section on the line 3-3 of Fig. 1.

Fig. 4 is a detail perspective view of the screen.

Fig. 5 is a detail perspective view of the band by means of which the screen may be secured in place.

Fig. 6 is a cross section on the line 6-6 of Fig. 1.

Fig. 7 is a view similar to Fig. 1, showing a slight modification of the invention.

Fig. 8 is a view similar to Figs. 1 and 7, showing a further modification.

Fig. 9 is a cross section on the line 9-9 of Fig. 8.

Fig. 10 is an elevation partly in section, showing a further modification of spark plug.

In the drawing, in which like numerals and letters of reference indicate like parts in all of the figures, 1 represents the outer or socket section of the plug which is of the usual construction and is provided with a wrench receiving face and with the threaded portion 2 that is adapted to enter the spark plug opening of an internal combustion engine. In the preferred form, the socket member also includes an extension 3, the sides of which are removed to leave side openings 4 for the admission of the combustible charge to the spark gap.

5 designates the pin which extends across and is in electrical engagement with the extension 3, so as to be electrically grounded to the engine casting, in the usual manner, and 6 represents the center electrode which is preferably provided with a shoulder 7 and a chisel-shaped end 8, adjacent to the pin 5 but spaced from the same to form the spark gap.

The inner electrode 6 is threaded and is, in the form shown in Figs. 1 to 7, permanently embedded in a filler 9 that is placed in the shell or outer socket member of the plug. This filler member is preferably constructed of a composition of cement and asbestos to form not only a rigid holding medium but an insulating medium as well and affords a permanent connection between the center electrode 6 and the pin electrode 5.

The inner electrode 6 extends upwardly through a wooden shank 10 that is provided with a projection 10^a to enter the upper portion of the metallic shell 1 and a second projection 10^b over which the screw cap 11 is fitted, the cap 11 being threaded onto the stem of the inner electrode 6 to hold the wooden section 10 in place, the wooden section 10 serving as a heat insulating medium

by which the spark plug can be handled when hot.

12 is the usual milled nut, by means of which the connecting wire from the ignition circuit may be attached to the electrode 6.

13 is a screen cup that is fitted over the sparking end 3 of the outer shell to inclose the electrodes at the spark gap and prevent the cylinder oil from fouling the points, thus reducing the danger of carbon deposits. Any oil that may accumulate on the screen 13 will be blown off by the explosion of the gases within the screen at the instant of ignition.

15 The form shown in Fig. 7 differs from the form shown in Fig. 1 in that the extension end 3 of the shell is omitted and the pin 16 is of the L-type threaded at 17 into the shell so as to be susceptible of being turned out, 20 as shown in dotted lines in Fig. 7, when it is desired to test the inner electrode 6.

If desired, one or more mica disks 19 can be interposed between the shoulder 7 and the metallic parts of the shell 1, although I believe that such use of mica will be unnecessary.

In the form shown in Fig. 8, the central electrode 6 is screwed into a sleeve 18 that is embedded in the filler 9 and thus electrode 6 30 may be adjusted to change the length of the spark gap by simply turning the electrode 6 within the sleeve 18, after loosening up the nut 11.

From the foregoing description taken in connection with the accompanying drawing, it is thought the complete construction, operation and advantages of my invention will be readily understood by those skilled in the art to which the invention relates.

40 Fig. 10 illustrates a further modification of construction of my spark plug in which the electrodes 5 and 21 are confined within the compass of the metallic body of the plug, the electrodes 21 being firmly embedded in 45 the metal of the plug and are exposed at

openings 20. A cement filling 9 is applied to the interior of the plug as shown, leaving the electrode points exposed.

What I claim is:

1. In a spark plug, an outer shell having a wrench receiving upper end, and a threaded section to enter the spark plug opening of an engine, an inner electrode, said inner electrode comprising a threaded rod extending above said shell, a heat resisting insulating 55 filler within said shell, and embedding a portion of said rod to retain said shell and rod in permanent relationship, said shell and said rod projecting beneath said filler, a pin carried by said shell to coöperate with the lower sparking end of said rod to form the spark gap, and a screen inclosing said pin and said inner electrode end at the spark gap to protect the same.

2. A spark plug comprising a shell adapted to be threaded into the spark plug opening of an engine, a pin carried by said shell, an inner electrode comprising a threaded rod entering said shell and projecting upwardly from the same, a filler of heat resisting electrically insulating material within said shell around said inner electrode, a heat insulating extension on said inner electrode in engagement with the upper end of said shell, a threaded cap on said inner electrode to retain said heat insulating extension in place, a milled nut on said inner electrode to coöperate with said cap for securing a circuit wire to the same, a screen cup secured on said shell over the "sparking points" to protect the same from fouling, and a threaded sleeve surrounding said inner electrode and in threaded engagement with the same and embedded in said heat resisting insulating filling.

JOSEPH T. NORMAN.
